UNITED STATES PATENT OFFICE.

ADOLPH TROST, OF CHICAGO, ILLINOIS, ASSIGNOR TO JOSEPH J. WHITE, OF CHICAGO, ILLINOIS.

ELECTRICALLY-HEATED FORMER FOR ROUNDING THE BACKS OF BOOK COVERS.

Application filed September 1, 1920. Serial No. 407,342.

To all whom it may concern:

Be it known that I, ADOLPH TROST, a citizen of the United States, residing at Chicago, in the county of Cook and State of Illinois, have invented a certain new and useful Improvement in Electrically-Heated Formers for Rounding the Backs of Book Covers, of which the following is a full, clear, concise, and exact description, reference being had to the accompanying drawings, forming a part of this specification.

The present invention relates to electrically heated formers for rounding the backs of book covers.

15 The invention is concerned with the operation of heating and rounding the backs of book covers after the completion of the covers and before they are applied to the book units in the so-called "casing-in" operation. 20 To the end that this operation of heating and rounding the backs of the covers—or "cases" as they are more technically termed in the book-binding art—shall be automatic and shall not interpose additional and time 25 consuming steps in the cycle of operations involved in the binding of the book, I have embodied the heating and rounding former directly in the casing-in machine, and have situated the rounding former in the machine 30 whereby the function of heating and rounding the backs of the covers is performed without modifying or retarding the operating cycle of the casing-in machine.

Referring to the specific objects of the 35 invention, one of the particular objects is to provide an improved construction of electrically heated rounding former which will be capable of convenient adjustment, whereby it may be readily adapted to the heating 40 and rounding of various sized book covers having different widths and curvatures of backs.

Another object of the invention is to provide a simple and inexpensive embodiment 45 of electrically heated former; and one which may be readily adapted as an appliance or attachment to standard constructions of casing-in machines.

Another object of the invention is to provide a construction of heating and rounding former which may be situated in the bottom 50 of the hopper which receives the book covers for feeding to the casing-in mechanism. The particular purpose of so situating the heating and rounding former is to provide

for a maximum time interval in which to complete the rounding operation, without slowing down the operation of the casing-in machine or necessitating an individual step or operation for performing this rounding function. The lowermost cover in the hopper is always in contact with the heating and rounding former, the covers successively dropping down upon the forming device as each preceding cover is fed forwardly from the hopper to the casing-in mechanism, and it will thus be seen that each cover is subjected to the heating and rounding action of the forming device from the moment the preceding cover is withdrawn from the hopper until the feeding devices have returned and are withdrawing the next succeeding cover which is in contact with the rounding former. The weight of the super-imposed pile of covers in the hopper imposes the necessary pressure upon the lowermost cover to enable it to properly co-operate with the heating and rounding former. One of the particular advantages of rounding the backs of the book covers directly in the casing-in machine is that the rounded curve given to the back of the cover is retained in better form by the practice of immediately applying the cover to the book, before the round has opportunity to become flattened or otherwise deformed.

A preferred manner of practicing my invention is illustrated in the accompanying drawings, in which:

Figure 1 is a fragmentary vertical sectional view through a commercial form of casing-in machine illustrating the application of our improved forming device thereto;

Figure 2 is an enlarged side elevational view of our improved heating and rounding former, a portion of the casing being broken away to illustrate the internal arrangement;

Figure 3 is a plan view of the heating and rounding former;

Figure 4 is a fragmentary sectional view through the hopper of the machine, illustrating the manner in which the backs of the book covers are rounded; and

Figure 5 is an end elevational view of the device illustrating a different rounding form mounted thereon having a wider rounding face.

The construction of casing-in machine illustrated in Figure 1, which I have chosen merely for the purpose of illustrating a

2

typical adaptation of the invention; is of a widely used commercial type embodying the inventions disclosed in Patents Nos. 672,010, 690,959, 716,959 and 832,082. I shall append only a brief description of this machine, sufficient to illustrate the co-operative relation of the present invention with the operating cycle thereof, as the general construction of this type of machine is a matter of common knowledge to those skilled in the art. The bed of the machine comprises a plurality of parallel guide bars 8, between which slide the feeding fingers 9 for feeding the rounded covers to the unbound books. Adjacent the left hand end of the guide bars 8 is erected a hopper or magazine 11 comprising two spaced magazine plates 12. The magazine or hopper 11 is adapted to receive a pile of completed covers, the covers resting upon the horizontal guide bars 8 and being maintained in vertical alinement by adjustable vertical guide members 14. The feeding fingers 9 are reciprocated to and fro beneath the pile 15 of covers 15 through the operation of suitable reciprocating rod mechanism, which need not be specifically described. On the return stroke to the left the feeding fingers—which are resiliently mounted—are depressed upon passing beneath the pile of covers 15. Upon the forward stroke to the right these feeding fingers engage the lowermost cover and feed it forwardly out from the bottom of the pile and transfer it over the unbound book, when the latter is in its lowered position between the paste boxes 16. The unbound books 17 are opened and placed upon a series of saddle plates 18 which radiate out from a vertical rotatable cylinder 19. Each saddle plate 18 with the book 17 thereon is revolved into position between two parallel paste boxes 16 and is then lowered between these paste boxes for the application of paste or other adhesive to the outer leaves of the book. This occurs while the feeding fingers 9 are moving through their return stroke to receive a new cover. When the book is in lowered position the paste boxes 16 close upon it, and at this point the feeding fingers 9 carry forward a new cover and position it directly over the book. As the book raises under the ascension of the saddle plate 18 paste is applied to the outside leaves thereof by the paste rollers 19 and simultaneously therewith the cover is forced down over the sides of the book. Coöoperating with the series of saddle plates 18 is a vertically reciprocating cross-head 21 which carries the mechanism for folding and jointing the book covers on the book. This cross-head reciprocates in predetermined relation with each saddle plate 18 in such a manner as to receive each book after the cover has been applied thereto and perform certain operations on the cover in-

cident in shaping and binding the cover to the book. We do not deem it necessary to go into detailed explanation of this mechanism as it is all within the common knowledge of the art and has no particular reference to the present invention.

The forming device which constitutes the subject matter of the present application is designated 23, and it will be observed that this forming device is situated in the bottom of the hopper 11 between the horizontal guide bars 8. As shown in Figure 4, this rounding former 23 is placed exactly in the center of the hopper 11 to be in alinement with the backs of the covers, and is supported between the two innermost guide bars 8—8 by screws 24. The structure of the former 23 comprises an elongated housing 25 of rectangular hollow cross-section. The interior of the housing 25 is cored out cylindrically for the reception of an electric heating element 26. This heating element is preferably a commercial or stock heater comprising a plurality of resistance heating elements embedded in a suitable body 90 of heat refractory material. Current is supplied to the heating element 26 through electrical conductors 27, which enter through an opening in the heat refractory end plate 28 which is screwed to the end of the housing 95 25. The other end of the cylindrical bore is closed by a plug 29. The screws 24 which support the rounding former thread into short tapped holes in the sides of the housing 26. These screws set into holes extending laterally through the central guide bars 8. By simply removing these screws the entire former unit can be drawn downwardly from between the guide bars 8.

The round is produced by an arcuate form 105 31 which is secured to the top of the housing 25 in position for shaping the back of the covers 15. The rounding form 31 is preferably mounted in such a manner that it may be quickly detached for the substitution 110 of forms having other degrees of curvature, and to this end the form is provided with a slot 32 at one end which engages under the head of a screw 33, and at the other end is provided with a depending bolt 34 which extends down below the bottom of the housing 25 and lies in a slot 35 in the end of the housing. Below the housing 25 the bolt 34 receives a wing nut 36, and by tightening this wing nut the form 31 can be securely held down upon the top of the housing 25. Different forms having different widths and different degrees of curvature, such as indicated at 31' in Figure 5 may be readily substituted for accommodating different styles 125 and sizes of covers by unloosening the wing nut 36 and withdrawing the slotted end 32 from under the screw head 33. The form 31 is adapted to be drawn down upon the flat surface of the housing 25 under sufficient 130

tension to insure maximum efficiency of heat conduction from the housing 25 to the form 31.

As will be noted from Figure 4, the weight 5 of the pile of covers 15 firmly presses the lowermost cover down upon the heated form 31 and impresses the desired curvature into the flexible back of the cover. The combined action of heat and weight on the cover 10 quickly produces the curvature in the flexible back, and immediately thereafter the feeding fingers 9 engage the edge of the cover and feed it forwardly into position for receiving a book, as previously described of 15 the casing-in operation. The next succeeding cover then drops down upon the heated form 31 and is in turn heated and rounded and fed forwardly to the casing-in mechanism as above described.

20 I claim as my invention:

1. In a rounding former for rounding the central portion of a book cover into a back, the combination of a housing, an electric cartridge heater in said housing, a 25 rounding form mounted on the upper surface of said housing and adapted to be

heated by said cartridge heater, and screw and slot fastening means for securing said rounding form to said housing and adapted to permit detachment of said rounding form 30 for the ready substitution of forms of different configurations.

2. In a casing-in machine, the combination of a magazine for receiving the book covers, means for feeding the covers from 35 said magazine to the casing-in mechanism, and an electrically heated rounding former in the bottom of said magazine for rounding the backs of said covers before feeding the same to said casing-in mechanism, said 40 rounding former comprising a housing extending parallel to and below the backs of the book covers, an electrical heating element in said housing, a convex form secured to the upper wall of said housing, and an attaching bolt extending between said form and an opening in said housing, whereby 45 said form can be conveniently substituted.

In witness whereof I hereunto subscribe my name this 13th day of August, 1920.

ADOLPH TROST.
